UNITED STATES PATENT OFFICE.

ROBERT P. HERON, OF SYRACUSE, NEW YORK.

TYPE-WRITER PLATEN AND OTHER ROLLER.

998,512.

Specification of Letters Patent.

Patented July 18, 1911.

Application filed October 2, 1909. Serial No. 520,603.

To all whom it may concern:

Be it known that I, ROBERT P. HERON, a citizen of the United States, and a resident of Syracuse, county of Onondaga, State of New York, and formerly a resident of Dolgeville, New York, have invented certain new and useful Improvements in Type-Writer Platens and other Rollers, of which the following is a specification.

My invention relates to typewriter platens, to casters and to other rollers in which the characteristics secured by it are desirable, and comprises a different embodiment of the broad idea set forth in my application filed of even date herewith. In this application, as well as in the other, I have illustrated and described the invention as applied to a typewriter platen and to a caster, and it is in fact especially adapted to the said uses. Nevertheless, as above suggested, I do not wish to be understood as limiting myself solely to these embodiments of it.

The rollers described in both applications have the common characteristics of having a surface of greater density than the backing. This characteristic is however obtained by different structures in the two applications. In this case instead of the disks illustrated in my other application I employ a strip of compressible material of peculiar shape wound helically and subjected to endwise compression.

In both the embodiments of the invention illustrated herein, the roller is constructed in the manner stated having a surface of higher density than the backing. The degree of absolute density of surface and backing may vary widely as may also their relative density, according to the needs to be met and the characteristics and properties required in rollers designed for different uses. The two embodiments shown in the drawings illustrate this. Obviously the caster must be much more dense than the platen.

Following the order of illustration in the drawings I shall refer first to the platen and then to the caster it being understood that much of the specification is of general application.

As suggested in my other application great annoyance has arisen in the use of typewriters from the excessive noise occa-

sioned by the platens now employed, and as applied to typewriter platens the object of my invention is to remedy this defect and to provide a thoroughly efficient platen which is not unduly expensive to manufacture. To this end making use of the principle above referred to by providing a striking surface of considerable density and a backing of less density, I have employed instead of disks a strip of felt of peculiar construction wound helically around a core and subjected to a high degree of compression. This winding closely covers the core and constitutes a homogeneous unitary structure. The roller may be made by the method hereinafter described.

The felt I employ is unsized and is of considerable hardness even before compression, sized felt being objectionable, if not wholly inadmissible in a platen, among other reasons, since the dry sizing is forced out as dust by the sharp impact of the type, and being furthermore harsh and likely to scratch the floor and to deteriorate when subjected to moisture, when used as a caster.

In rollers formed of windings of compressible material it is difficult to secure a smooth dense surface, but by the use of my invention this may be accomplished and a surface may even be secured of the exceedingly high density necessary in rollers whose function is to support weight without suffering deformation, the backing being sufficiently dense to support the surface properly.

My invention consists in a roller, the preferable embodiments of which are illustrated and described herein, whether designed to sustain the impact of type-bars, to endure pressure, to uphold weight or for other purposes within the scope of the claims.

Referring to the drawings, Figure 1 is an elevation of a typewriter platen embodying my invention, the platen being broken away at each side of the middle, and parts being shown in section to make clear its construction. Fig. 2 is an elevation chiefly in section of a portion of the platen as formed by the application of a strip of different shape from that shown in Fig. 1. The windings in both Figs. 1 and 2 are shown as under compression. It is to be understood, however, that in order to illustrate the difference in density of the different parts of the wind-

ing, an exaggerated space has been shown between adjacent spires thereof. It will nevertheless be apparent that the strip will be so proportioned and the pressure so regulated that adjacent spires will be in more or less intimate contact at all points of their contiguous surfaces or that there will be but a slight space between them near their inner surfaces. Fig. 3 is a longitudinal section 10 through adjacent spires of a winding formed by the application of the strip shown in Fig. 2. Fig. 4 is a similar view of adjacent spires of the winding formed by the application of the strip shown in Fig. 1. Figs. 3 15 and 4, both show the windings before compression. Fig. 5 is a detailed view of the plate at the left end of the platen one end of the winding and the means whereby it is fastened. For clearness, the parts are illustrated as somewhat out of their normal positions. Fig. 6 is a perspective view of a 20 caster embodying my invention. Fig. 7 is an elevation of the caster parts of the wheel and its supporting means being shown in section, and Fig. 8 is a sectional elevation 25 of the parts making up the caster wheel in their unassembled position before they have been subjected to compression.

Referring to Figs. 1-5 which illustrate the 30 application of the invention to a typewriter platen; 1 is the usual platen rod. 2 is the tube surrounding the same. 3 is a core or sleeve suitably of wood on which is wound the strip 4, preferably of felt in which the 35 ends of the fibers are presented to the outside of the strip. 5 is the plate at the left end of the platen and 6 is the ratchet plate on its opposite end. As in my disk construction, the tube 2 is internally screw-threaded at its ends and bushings 7, 7, externally screw-threaded to co-act with the ends of the tube are provided. These bushings are each retained in position by a set screw 8 as shown in Fig. 1. 9 represents the 40 striking surface and 10 the backing, which by reason of the form of the strip are of different densities. The strip 4, which may vary greatly in cross-section, has its outer surface wider than its inner surface. This 45 makes it possible to secure a surface of the high density necessary and results in a backing of less density than the surface. The strip 4 is of peculiar cross section, its inner surface 11 being parallel with its outer surface 12 and one side 13 being at substantially right angles with these parallel surfaces. The other side 14, however, slants inwardly 50 toward the first mentioned side. In Fig. 3, the side 14 is shown as a continuous bevel 60 from the outer surface to the inner surface of the strip. In Fig. 4, however, this side extends inward at 15 substantially at right angles with the outer surface and then slants at 16 to the inner surface making in section a broken line.

The sides of the strip need not make right angles with the other surfaces, and they may be curved or partly straight and partly curved. The forms shown, however, I regard as the best. Of these that shown in 70 Fig. 4 ordinarily gives a thicker surface but the form shown in Fig. 3 gives a structure which is perhaps more completely unitary when the parts are in readiness for use, the surface, gradually shading into the backing. 75

The platen may be made by the following method: A strip of the desired shape and of suitable length is prepared, its ends being tapered. It is then wound helically around the wooden core 3 which has first been 80 placed in position on the tube 2 within which is the rod 1. The end plates with their respective bushings are placed on rod 1 and the tapered ends of the strip are put through the slanting slots 17 in the said 85 plates. The strip is then twisted preferably by the hands and by turning the plates, so that it tightens around the center of the roll, the ends are pulled out through the slots 17 in the end plates as may be necessary and compression is at the same time exerted by means of these end plates by screwing in one or both of the bushings which are provided with wrench holds. Endwise compression tends to spread the 90 strip away from the core. Twisting tends to draw it toward the core. By twisting and compressing simultaneously the strip may be made to lie flat against the core and to present a smooth surface, while at the same 95 time possessing the requisite density in its striking surface and backing. Clamping dogs 18 having outwardly directed teeth 19 and held in position by set screws 20 co-acting with depressions 21 in the backs of 100 the dogs, permit the ends of the strips to be pulled out through the end plates but retain them against movement in the other direction. When the proper degree of compression has been secured, the said screws can be 105 tightened so that the dogs will hold the strip permanently in position. As shown, these dogs are formed of an angular piece of metal, the outer part of which 22 forms a tail which projects beyond the slot 17 and 110 more than covers it having a bearing surface against the outer face of the plate. The parts are so proportioned that, if further compression becomes necessary in use, this 115 can be obtained by screwing up the bushings still further. To this end both the tube 2 and the core 3 are shorter than the portion of the roller made up of the strip, so that even when the covering is under compression there is still a space at each end 120 between the plates and the tube and core. In lieu of this process the strip may be wound by well known machinery and may be compressed in a power press of known 125 type. Lateral expansion may be prevented 130

by any well known means as a press chamber or tube of suitable shape.

It will be understood, of course, that the dimensions of the strip and its shape depend largely upon the functions to be performed by the individual roller of which it is to constitute the covering and are to a considerable extent determined thereby.

The specification thus far while containing much that is of general applicability to various kinds of rollers has dealt more particularly with typewriter platens. At this point the application of my invention to casters will be taken up and briefly discussed, an effort being made to avoid needless repetition.

In casters there is a necessity for wheels which will support weight without deformation and which nevertheless will not injure the floors. A material which admirably fulfills the latter requirement is unsized felt, and when this is given the first requisite, that of power to resist deformation, a thoroughly satisfactory caster results. I have found that my construction already described, is particularly suitable to casters and produces a caster which meets both requirements being sufficiently dense to retain its form while at the same time retaining the natural characteristics of felt which make it particularly suitable for use in a caster. In applying my construction to casters I make the surface more dense than the backing thus insuring a very hard surface of perfectly symmetrical and unvarying contour. I also compress the backing, although to a lesser degree than the surface, sufficiently to sustain the latter.

Referring to Figs. 6, 7, and 8 the caster wheel is rotatably mounted on pin 23 in the jaws of the caster horn 24 to which is secured the pintle 25. A caster socket 26 is illustrated in Figs. 6 and 7. The caster wheel consists of the core 3' on the sleeve 2' and the covering is made up of the strip 4' helically wound on the core compressed together and retained in position by the plates 5' 6' over the edges of holes in the center of which the ends of the sleeve 2' are beaded at 27. It will be noted that no fastening means for the ends of the strip are provided the plates and strip being highly compressed together so that the ends of the strip are permanently retained in position. The more highly compressed surface or tread is designated by 9' and the backing by 10'. The strip has the form shown in Fig. 4 and in Fig. 8, having a part of its side beveled or cut away as indicated at 16'. As above suggested the depth, thickness and shape of the strip may be varied, it being possible to dispense with the core altogether should this seem desirable. The nature of the strip and the extent to which it is compressed depend largely on the size of the finished

caster and on the work it is to perform. Casters designed to support heavier weights are ordinarily larger and may be denser.

In Figs. 1 and 6 the meeting line of the adjacent spires of the helix is shown for clearness although in fact it would hardly be observable. In Fig. 7 which shows the helical winding under compression, I have indicated the difference in density of the surface and backing but have not shown any intermediate spaces between adjacent spires. They would not in fact exist in the finished caster, the adjacent spires being to some extent merged together.

The elements making up the caster wheel are shown unassembled in Fig. 8. They are assembled and compressed into the complete caster wheel in any suitable power press. During compression, as suggested in connection with the description of the method of making the typewriter platen, lateral expansion may be suitably guarded against by the provision of a press chamber of the proper shape having unyielding walls and any tendency of the end plates to embed themselves in the adjacent parts of the strip may be prevented by providing each end of the press chamber with an annular ring surrounding the end plate and terminating in the plane of its inner face or preferably in a bevel beyond said face toward the strip. While a caster wheel made with screw-threaded bushings like the typewriter platens shown in Figs. 1 and 2, could be made by the manual process described earlier in the specification, it is obvious that the construction illustrated in Figs. 6-8 is neater and more compact, and that the well known method just referred to is better adapted to making casters, not only because of the increase in speed it gives, but because a higher density is more readily and certainly secured. As in the case of the platen I do not find it necessary to use water, sizing or any other liquid but prefer to compress the disks while dry. After the wheel has been formed in this manner it is a thoroughly good caster and may be used without finishing, but its rather rough and unfinished appearance is unattractive to the eye. It is therefore treated by any of the methods commonly employed for treating raw felt surfaces and raw surfaces of other compressible materials so as to eliminate any inequalities, insure perfect uniformity in the contour of the wheel, and improve its appearance.

Having described the nature and objects of the invention, what I claim as new and desire to secure by Letters Patent is:

1. A roller having a helical winding strip wound to form a unitary covering and comprising a surface and a backing therefor, the surface being of greater density than the backing.

2. A roller having a helical winding of compressible material under compression constituting a surface and a backing therefor the surface being of greater density than the backing.
3. A roller comprising a helical winding of compressible material having contacting sides and constituting a surface and a backing, the backing having a part of one of the 10 contacting sides cut away, a support for said covering, and means for compressing the covering whereby the surface is made more dense than the backing.
4. A roller comprising a felt winding constituting a surface and a backing therefor, 15 said winding consisting of a strip of greater width near the surface of the roller than next its center, and means for retaining said winding under compression, whereby the 20 surface is maintained at a higher density than the backing.
5. A roller comprising a strip wound helically having greater width near the surface of the roller than nearer its center and constituting a surface and a backing, the surface being under a higher degree of compression than the backing, and means for retaining this relation.
6. The combination of a support with a 30 helical strip of compressible material wound thereon, under pressure having adjacent spires in contact at or near the outer surface of the strip at certain stages of compression, spaces being left between the spires 35 adjacent the support, and means for further compressing the strip to reduce the space between the spires.
7. A roller provided with a helical winding of felt, the winding having a compressed 40 backing and a compressed annular portion surrounding it, said annular portion being of a greater density than the backing.
8. A roller having a covering comprising a strip of compressible material said strip 45 having a long side and a short side and wound helically with the long side in contact with the short side, and means for compressing the covering in the direction of the length of the roller.
50. 9. A roller having a covering comprising a strip of compressible material said strip having a side part of which is beveled and a short side and wound helically with the short side and the beveled side in contact, 55 and means for compressing the covering in the direction of the length of the roller.
10. A roller comprising a compressible winding, a support therefor, plates near the ends of said support provided with holding 60 means for the ends of the said winding, and means for altering the position of the plates to compress the winding and to retain it under torsion.
11. A roller comprising a compressible winding, a support therefor comprising a tube, two plates near the ends of said tube, dogs adjustable in said plates and having outwardly faced teeth to retain the winding against endwise movement in one direction while permitting it in the other direction, 70 and bushings supporting said plates rotatably and adapted to be screwed into the ends of the tube to force the plates toward each other.
12. In a roller an end plate having a diagonal slot therein, an angular dog in said slot having a tail slidable on the outer face of the plate and provided with outwardly pointed teeth, and means for adjusting the position of the dog.
13. A roller comprising a compressible winding, a support therefor, plates near the ends thereof provided with means for holding the ends of the winding against movement in one direction while permitting it in the other, said plates being rotatable with respect to each other to twist the winding, and means for forcing the plates toward each other to compress the winding and to retain it under torsion.
14. A roller comprising a compressible winding, a support therefor, plates near the ends thereof provided with means for holding the ends of the winding against movement in one direction while permitting it in the other, said plates being rotatable with respect to each other to twist the winding, and means for forcing the plates toward each other to compress the winding and to retain it under torsion, said winding when under compression extending beyond the ends of the support.
15. A typewriter platen comprising a support, a helical winding of felt thereon constituting a striking surface and a backing therefor, said winding consisting of a strip of greater width near the surface of the roller than next its center, and end plates, one of which is a ratchet plate, for retaining said winding under compression, whereby the striking surface is maintained at a higher density than the backing.

Signed by me at Syracuse, N. Y., this 20th day of September 1909.

ROBERT P. HERON.
